OSCAR N. EARTHOM AND TOLBERT GALLAHER, OF ADENA, OHIO, ASSIGNEES OF ONE-THIRD
TO GEORGE W. TIDRICH, OF DILLONVALE, OHIO.

MINE-DOOR.

No. 870,420.

Specification of Letters Patent.

Patented Nov. 5, 1907.

Application filed June 21, 1907. Serial No. 380,064.

To all whom it may concern:

Be it known that we, OSCAR N. EARTHOM and TOLBERT GALLAHER, citizens of the United States, and residents of Adena, in the county of Jefferson and State 5 of Ohio, have invented a new and Improved Mine-Door, of which the following is a full, clear, and exact description.

This invention relates to mine doors and more particularly to that class of doors used in connection with 10 mine drifts or levels.

The object of the invention is to provide a simple, strong and efficient mine door having means adapted to be actuated by a car for ore, coal and the like, for operating the door.

15 The object of the invention is to provide a simple, strong and efficient mine door for regulating the ventilation in mines and other similar workings, which is operable by a car for ore, coal and the like, and which is so constructed that it opens and closes transversely 20 of the mine passageway, thereby requiring less room for its operating than a swinging door.

The invention consists in the construction and combination of parts to be more particularly described hereinafter and fully set forth in the claims.

25 Reference is to be had to the accompanying drawings forming a part of this specification, in which similar characters of reference indicate corresponding parts in all the figures, and in which

Figure 1 is a plan view of a mine level, drift or other 30 passageway, showing my invention applied thereto; Fig. 2 is a similar view showing the mine door in a different position; Fig. 3 is an end elevation of the invention; Fig. 4 is a longitudinal section of the mine passageway, showing one of the wings of the mine door in a 35 closed position; Fig. 5 is a vertical section on the line 5-5 of Fig. 1; and Fig. 6 is a perspective view of a detail.

Before proceeding to a more detailed explanation of my invention, it should be understood that it is customary 40 to employ doors in the drifts, levels, galleries or other passageways of mines, such for instance, as coal mines, for the suitable regulation of the ventilation in the mine. These doors must necessarily be opened each time a coal, ore or other car travels through 45 the passageway and must be closed again subsequent to the passage of the car beyond the door, for if the doors are allowed to remain open for any length of time serious difficulty with the ventilating system is liable to occur. In order to save time and labor in the operation 50 of mine doors, I provide a device of this class which is automatically operated by the car itself, and which therefore needs no supervision or attendance on the part of operator driving the car. At the same time my mine door can be easily opened independent of the

car-actuated mechanism. In various kinds of mines 55 swinging mine doors are often employed, which are usually arranged to swing in but one direction. If the normal draft of the air in the mine passageway is in a direction opposite to the swinging direction of the door, the pressure of the air normally tends to hold the door 60 shut. If the direction of the draft is in the same direction as the swing of the door, the pressure of the air will tend to open the door, and unless suitable means are provided for powerfully holding the door in the closed position there will often be a constant escape of the air 65 through the slightly opened door, and this state of affairs tends to cause faulty operation of the ventilating system. To obviate this difficulty I provide a mine door which opens transversely of the length of the mine passageway, so that the operation of the door is quite 70 independent of the normal direction of the draft of the air in the passageway. To permit of this arrangement I employ doors of flexible material, such as canvas, provided with suitable bracing strips of wood or metal. When the doors are in the closed position the flexible 75 material is extended across the passageway. When the doors are opened, the flexible material can fold up to permit the movement of the doors in a direction substantially at right angles with the walls of the passageway; that is, transversely of the latter. 80

Referring more particularly to the drawings, 1 represents a passageway of a mine such as a level, drift or gallery. The mine is shored or braced with the usual vertical and horizontal timbers 2 and 3 respectively, and the cross timbers 4 carried by the vertical timbers. 85 Track rails 5 carried by ties 6 of any preferred or common form, are laid longitudinally of the passageway and upon these rails the mine cars travel. The latter may be of any type and are used for transporting the ore or coal from the mine to the surface. Each mine 90 door comprises similar wings each arranged to extend substantially half-way across the passageway. Each wing has at the outer end a door upright 7 of wood, metal or any other suitable material. Fastened to the inner edge of the upright 7 is a flexible body 8. The 95 flexible body of each door wing may consist of wooden or metal slats joined by a fabric backing, or may consist of slats suitably hinged together. The vertical edge of each body 8 at the side opposite to the upright 7 is secured to a suitable timber 9, carried at the side 100 of the passageway by one of the usual mine timbers. The flexible body is secured to the timber 9 by means of a metal fastener 10, having an edge 11 folded upon itself to clamp the flexible body. The opposite edge of the body 8 is secured to the uprights 7 by means of 105 a similar fastener 12. Rigid with each of the uprights 7 and at an angle therewith are arms 13 and 14, near the upper and lower ends of the uprights respectively.

The arms 13 and 14 are normally at an angle with the length of the passageway, and have the ends remote from the uprights secured to a vertical shaft 15, pivotally mounted in suitable brackets 16 at the side of the passageway. The arm 14 has an extension 17 at the side of the shaft 15 remote from the door, which is pivotally connected with a bell crank lever 18 mounted in a suitable bracket 19 carried by one of the timbers at the side of the passageway. The bell crank lever 18 and the arm 14 are connected by means of a short link 20. The bracket 16 has a lateral ear 21. The ear 21 has an opening in which is slidably arranged a rod 22 having the lower end secured to an arm of the bell crank lever 18; near the opposite ends the rod 22 has 15 slidable collars 23. A helical spring 24 is arranged upon the rod 22 between the collars 23, and resists the movement of the bell crank lever 18. Thus as each of the door wings is moved toward the corresponding side of the passageway the arms and the shaft are operated, 20 the extension 17 of the arm 14 swinging the bell crank lever about its pivot against the resistance of the helical spring. Correspondingly, when the door wings are released, the spring operates the bell crank lever 18 which in turn operates the arm 14 to move the door wing into 25 the closed position. At the opposite side, each of the door wings has an arm 25 pivotally mounted at the side of the passageway upon a suitably hinged bracket 26. The arm 25 has a hinged part 27 at the end adjacent to the door wing, which in turn is hinged to the door 30 upright 7. The part 27 of each arm is normally at an angle with the body of the arm when the door wing is in the closed position. When the door wing is advanced toward the side of the passageway, the hinged part 27 of the arm swings toward the body of the arm, 35 to shorten the latter between the door uprights and the point of attachment of the arm 25 at the hinged bracket 26. It is of course necessary for one of the supporting arms at one side of the door wing to shorten as the latter is moved toward the side of the passageway. 40 On the same side of the mine door as the arms 25 of each wing, are opposite, similar, actuating rails 28. The actuating rails 28 are preferably formed of angle bars having vertical flanges disposed inwardly with respect to the track. The ends remote from the door 45 wings are curved outwardly and the opposite ends have offset portions 29 provided at the ends with slots 30. The normal position of the actuating rails when the door wings are closed is at an angle with the track rails and extending thereacross, the actuating rails being inclined toward each other and being at the greatest distance apart at the ends remote from the door wings. At the opposite side of the latter are similar, actuating rails 31 having at the ends adjacent to the door wings, outwardly disposed extensions 32 carrying pins 33 arranged to slide in the slots 30 of the actuating rails 28. The actuating rails 31 have laterally pivoted arms 34. At the sides adjacent to the sides of the passageway, the arms 34 present elongated slots 35 in which are slidably arranged pins 36 carried by the arms 13. The arrangement is such that when the door wings are in the closed or normal position the pins 36 are located adjacent to the inner ends of the slots 35; thus the doors can be opened independent of the actuating rails 31, the pins 36 sliding freely in the slots 35. When the actuating 60 rails are moved outwardly however, the inner ends of 65

the slots 35 engage the pins 36 and force the wings outwardly to open the same. The ends of the rails 28 and 31 remote from the door wings are pivotally mounted in the slots 38 of slide blocks 37. The slide blocks 37 are located in guide grooves 39 in supporting members 40 arranged at the sides of the passageway. The supporting members 40 are preferably carried on a cross timber 41 arranged on the floor of the passageway. At the back each supporting member 40 has an upward extension 42 upon which is mounted a plate 43. Between the plate 75 43 and the supporting member 40 the slide block is arranged to slide and presents at the rear, a rod 44. The rear end of the plate 43 is downwardly disposed to form a toe 45 presenting an opening in which the rod 44 is slidably arranged. A helical spring 46 is mounted upon the rod 44 between the end of the slide block and the inner face of the toe 45, to resist the sliding movement of the block 37. By means of this arrangement, the actuating rails 28 and 31 are resiliently pivoted, so that when a car moving along the track comes into engagement with the actuating rails the jar incident to the contact is absorbed by the spring 46, and thereby the danger of derailment due to the actuating rail is minimized. Although the jar or shock is absorbed by the spring, the resistance of the latter is sufficient to hold 90 the actuating rails firmly and to permit the car to swing the latter outwardly to open the door wings.

Having thus described our invention, we claim as new and desire to secure by Letters Patent:—

1. In a device of the class described, a flexible door arranged to open and close transversely of the mine passageway, a car-actuated member independent of said door and adapted to engage said door to open the same when said member is actuated, resilient means for normally holding said door in a closed position, and a resiliently-held block, said car actuated member being pivotally mounted upon said block at the end first engaged by the car. 95

2. In a device of the class described, a flexible door, a swinging arm having an end section at a side of the mine passageway and adapted on operation to engage said door at the opposite end to open the same, and car-actuated mechanism controlling said arm, said door being operable independent of any movement of said arm. 105

3. In a device of the class described, a flexible door arranged to open and close transversely of the mine passageway, a swinging arm having an end secured at a side of the mine passageway and adapted on operation to engage said door at the opposite end to open the same, said arm normally lying at an angle with the longitudinal direction of said passageway, and car-actuated mechanism controlling said arm, said door being operable independent of any movement of said swinging arm. 110

4. In a device of the class described, a flexible door arranged to open and close transversely of the mine passageway, arms at opposite sides of said door and adapted on operation to engage said door at the present ends to open same, the opposite ends of each arm being pivoted at a side of the mine passageway, and car-actuated mechanism controlling one of said arms to operate said door, said door being operable independent of any movement of said arms. 120

5. In a device of the class described, a door arranged to open and close transversely of the mine passageway, a swinging arm having an end pivoted at a side of the mine passageway and adapted to engage said door at the opposite end to open the same when said arm is operated, said arm normally extending into said passageway when said door is closed, means for holding said arm in a normal position, and a member controlling said arm and adapted to be actuated by a car, said door being capable of operation independent of any movement of said arm and said member. 130

6. In a device of the class described, a door arranged to open and close transversely of the mine passageway, a swinging arm having an end secured to said door and the opposite end pivoted at a side of the mine passageway, a spring-held lever operatively connected with said arm to hold the same in a normal position with the door closed, and a pivoted member adapted to engage said arm to operate said door when said member is actuated by a car. 5
7. In a device of the class described, a door arranged to open and close transversely of the mine passageway, a swinging arm having an end secured to said door and the opposite end pivoted at a side of the mine passageway, said arm normally extending from the side of the mine passageway to hold said door in a closed position, a lever, a spring holding said lever in the normal position, a link operatively connecting said arm and said lever, and a pivoted member controlling said arm and adapted to be actuated by a car. 10
8. In a device of the class described, a door arranged to open and close transversely of the mine passageway, a swinging arm having an end secured to said door and the opposite end pivoted at a side of the mine passageway, a lever, a link operatively connecting said lever and said arm, a spring resisting the movement of said lever, a pivoted member operable by a car and adapted to engage said arm to operate said door when said member is actuated, and means for resiliently holding the end of said member first engaged by a car. 15
9. In a device of the class described, a door arranged to open and close transversely of the mine passageway, an arm having an end secured to said door and the opposite end pivoted at a side of the mine passageway, a second arm at the opposite side of said door remote from said first arm and having an end hinged to said door and the opposite end pivoted at a side of the mine passageway, a lever, a link operatively connecting said lever and said first arm, a spring resisting the movement of said lever, a member having a pivoted arm engaging said first arm and adapted to be actuated by a car, and a second member at the side of said door remote from said first member and adapted to be actuated by a car, said members being pivotally connected. 20
10. In a device of the class described, a door arranged to open and close transversely of the mine passageway, an arm having an end secured to said door and the opposite end pivoted at a side of the mine passageway, a member adapted to be actuated by a car, a second member at the side of said door remote from said first member and adapted to be actuated by a car, said second member having a slot near the end, said first member having a pin operatively arranged in said slot, and resili- 25
- ently-held blocks, said members being pivoted on said blocks near the ends first engaged by the car. 55
11. In a device of the class described, a flexible door arranged to open and close transversely of the mine passageway, an arm having an end secured to said door and the opposite end pivoted at a side of the mine passageway, resilient means for resisting the movement of said arm, a second arm at the side of said door remote from said first arm and having a hinged part pivotally mounted at said door, said second arm having the end remote from said hinged part pivotally mounted at a side of the mine passageway, and a plurality of members at the opposite sides of said door and controlling said first arm to operate said door, said members being adapted to be actuated by a car. 60
12. In a device of the class described, a flexible door arranged to open and close transversely of the mine passageway, an arm having an end secured to said door and the opposite end pivoted at a side of the mine passageway, resilient means for resisting the movement of said arm, a member having a pivoted arm presenting a slot, said first arm having a pin engaging said slot, a second member at the side of said door remote from said first member and operatively connected with said first member, the ends of said members remote from said door being resiliently held. 65
13. In a device of the class described, a flexible door arranged to open and close transversely of the mine passageway, an arm having an end secured to said door and the opposite end pivoted at a side of the mine passageway, a lever, a link operatively connecting said arm and said lever, a spring resisting the movement of said lever, a second arm having a hinged part pivotally mounted at said door, said second arm having the end remote from said hinged part pivotally mounted at a side of the mine passageway, brackets at each side of said door, blocks slidably arranged upon said brackets, springs resisting the movement of said blocks, members pivoted on said blocks and extending toward said door and normally at an angle with the longitudinal direction of the mine passageway, said opposite members being operatively connected, one of said members having a pivoted slotted arm engaging said first arm to control said door. 70
